BORIS P. ANDREIANOFF, OF MOSCOW, UNION OF SOVIET SOCIALIST REPUBLICS

DEVICE FOR RETAINING TRACK RAILS

Application filed February 28, 1930, Serial No. 432,080, and in Union of Soviet Socialist Republics
March 2, 1929.

My invention relates to rail retaining devices and has a particular reference to attachments for preventing track rails from becoming displaced under tractive efforts of heavy trains.

Railroad rails are often subjected to some very heavy strains caused by acceleration or deceleration of fast or heavy trains. These strains tend to shift or displace the rails in a direction of train movement. Practice has shown that ordinary methods of securing rails to ties by means of spikes and tie plates are usually inadequate, as even the ties themselves gradually become shifted. The vibrations and strains also gradually loosen the tie plates allowing the rails to slip over them. In order to eliminate the possibility of such rail displacement I provide each rail with one or several hinged tie rods extending from a heavy plate buried under the track. The tie rods are placed at an angle being inclined from the plate to the rail in a direction of train movement. Such angular position does not interfere with the normal settling of the track in its ballast. At the same time any longitudinal stresses applied to the rail produce a pull on the tie rod causing it to swing down on its pivot on the buried slab, thereby tending to press the rails and the ties to the road bed. This pressure, in turn, tends to increase the adhesion of the rails and ties to the roadbed, preventing their slippage, in addition to the actual holding action of the tie rods between the slab and the rails.

My invention is more fully described in the accompanying specification and drawings in which—

Fig. 1 is a sectional elevation of a railroad track showing my holding arrangement, Fig. 2 is an end view of same, also in section, Fig. 3 is an enlarged view of the rail clamp, Figs. 4 and 5 detail views of the clamp plate, Fig. 6 is a sectional view of a modified arrangement, Fig. 7 is a plan view of a wooden slab, Fig. 8 is a detail view of a clamp for a wooden beam, Fig. 9 is a detail view of a steel tie with clamps for the rail, Fig. 10 is a special clamp for the rail and wooden tie, Fig. 11 is an arrangement adapted to prevent radial displacement of the track, Fig. 12 is a

modified arrangement of same, Fig. 13 is a sectional elevation of the track showing a combined arrangement for preventing rail slippage in all directions, and Fig. 14 is a diagram illustrating the action of my device. 55

My rail holding device consists of a heavy slab or plate 1 made of a reinforced concrete and buried under a rail 2 at a certain depth in a ballast 3. A hole or depression 4 is provided for the slab in the earth 5 under the ballast.

In order to increase the frictional adhesion of the slab to the ballast, the lower side of the slab is provided with transverse grooves 6. The depth of these grooves can be preferably 65 made equal to about one half of the thickness of a crushed stone used for ballast. If sand is used then it is advisable to place a layer of crushed stone directly under the slab.

The upper side of the slab is provided with 70 shallow rectangular (or of any other suitable shape) depressions 7 which also tend to increase the adhesion of the slab to the ballast. If crushed stone is used, then instead of rectangular depressions grooves can be used 75 similar to the grooves 6.

Clevis bolts 8 are inserted in the slab and are firmly secured between top and bottom holding metal plates 9 and 10. Tie rods 11 are pivotally connected with the clevises by 80 means of pins 12. These tie rods extend to the rails 2 at an angle in a general direction of the train movement. The upper ends of the tie rods are pivotally mounted on pins 13 supported in rail plates 14. The rail plate 85 represents a piece of a channel steel bent as shown and provided with holes 15 for the pin 13 and slots 16 for a bolt 17.

The rail plate is placed under the rail as shown in Fig. 3 and is clamped on both sides 90 with clamps 18 and bolts 17.

The rails 2 are supported on ties 19 of an ordinary construction and are secured with tie plates 20 and spikes 21.

The arrangement shown in Fig. 1 is made 95 specially for a one way track with trains moving to the left. The pull on the rail from the train is then transmitted to the tie rods 11 tensioning them, which tension is transmitted to the buried slab 1. The hori- 100

zontal pull on the tie rods, at the same time, causes them to depress the rail down and to press it still harder against the road bed. This action is illustrated in Fig. 14, the depressed position being shown with dotted lines.

A modified arrangement is shown in Fig. 8. Here a single tie rod is used for the rail 2. Its lower end is pivotally connected with a clamp 22 which encircles a wooden beam 23, there being one beam for each rail. The two beams are connected by wooden boards 24 fastened to the beams by spikes 25. These beams with the boards form a common slab 15 for two rails.

Another modification is shown in Fig. 11 which is especially adapted for preventing transverse displacement of the track rails, for instance, on the curves. For this purpose the rails are connected with a metal tie or bar 26 fastened to ordinary ties 19 with bolts 27. The rail is fastened to the bar 26 by means of clamps 28 and bolts 29. Instead of using a bar 19 the rails can be supported on brackets 30 (Fig. 10) bolted to the tie with bolts 31 and provided with supporting lugs 32 for the side of the rail similar to ordinary fish plates. The tie rods 33 (Fig. 11) extend from the rail clamps to clevis bolts 8 in large slabs 34 extending under both rails. The tie rods extend at an angle and cross each other so as to offer resistance to either direction of the rail shift, to the right or to the left.

In cases when the side strains are very large a double set of cross tie rods 35 may be used (Fig. 12), the rods extending in both directions from each rail to the large slab 36.

A combined arrangement is shown in Fig. 13 with longitudinal tie rods 11 and transverse rods 33 attached to the same slab 37 which extends under both rails 2. The rail attachments 38 are shown of a simplified form adapted to be welded to the lower surface of the rail and provided with clevises 39 for bolts 40.

Important advantages of my arrangement are that it provides a means for securely holding the rails on the track, preventing them from longitudinal and transverse displacements under heavy strains from passing trains, thereby rendering the track more permanent and eliminating necessity for frequent repairs and relaying of the track rails.

I claim as my invention:

1. In a track retaining device, the combination with horizontally extending massive slabs buried in the ballast under track rails, and tie rods extending from said slabs to said rails and pivotally connected with said slabs and said rails, said slabs being placed in depressions in the ground under said ballast.

2. In a track retaining device, the combination with horizontally extending massive slabs buried in the roadbed under track rails, tie rods extending from said slabs to said

rails, and metal members permanently connected with said slabs, said rods being removably connected with said metal members and said rails.

3. In a rail retaining device, the combination with slabs buried under the ballast under track rails, tie rods extending from said slabs to said rails, channel-shaped members placed longitudinally with their edges against the bottom surface of the rails, clamps adapted to hold together said members and said rails, bolts passing through said clamps and said members in a cooperation with said clamps, and means to removably connect the ends of said tie rods with said channel-shaped members.

In testimony whereof I affix my signature.

BORIS P. ANDREIANOFF.
